UNITED STATES PATENT OFFICE.

NEIL A. FOWLER, OF CHICAGO, ILLINOIS, ASSIGNOR TO WIREBOUNDS PATENTS COMPANY, A CORPORATION OF MAINE.

MACHINE FOR MANUFACTURING BOX BLANKS.

1,402,289.

Specification of Letters Patent.

Patented Jan. 3, 1922.

Application filed June 17, 1918. Serial No. 240,424.

To all whom it may concern:

Be it known that NEIL A. FOWLER, a citizen of the United States of America, and a resident of Chicago, in the county of Cook and State of Illinois, has invented an Improvement in Machines for Manufacturing Box Blanks, of which the following is a specification.

The object of this invention is to produce 10 a machine capable of assembling cleats, sheet material and binding wire into a foldable box blank, the sections of which are so related to each other that they may be folded up into an open-ended box to which may 15 be secured, if desired, suitable closing ends.

The accompanying drawings illustrate the invention.

Figure 1 is a side elevation of the machine from the friction-drive side.

20 Figure 2 is a side elevation from the positive-drive side, the cleat-feeding chains being omitted.

Figure 3 is a plan of a positive-drive mechanism.

25 Figure 4 is a fragmentary diagram of one section of the positive-drive mechanism.

Figure 5 is a horizontal section on a plane just below the stapling mechanism.

In the drawings, 10 indicates the main 30 frame having two parallel cleat guides 11, 11, one of which is fixed and the other of which is laterally adjustable in the machine.

At the feed end of each of these guides is a shaft 12, which carries idler sprockets 35 13. There are eight of these sprockets for each guide, four on each side, and running over these sprockets are four pairs of chains 14, 15, 16 and 17, which are connected in pairs by cross bars 14', 15', 16' and 17', 40 respectively.

At the delivery end of the machine, there are four shafts 19, 20, 21 and 22, each of which carries sixteen sprockets wheels 23 arranged in pairs to receive the chains 14, 45 15, 16 and 17.

All of the sprocket wheels on each shaft are idlers except that two appropriate pairs are fastened to each shaft so that shaft 19 has a positive connection with chains 14, 50 shaft 20 a positive connection with chains 15, shaft 21 a positive connection with chains, 16, and shaft 22 a positive connection with chains 17.

By this arrangement each of the shafts 55 19, 20, 21 and 22 positively controls one

of the four cross bars associated with each cleat guide 11.

The main drive shaft 24 is connected by a sprocket chain 25 with a sprocket wheel 26 on a stud shaft 27, connection with the 60 shaft 27 being established by means of a clutch 28 controlled by the foot pedal 29.

Shaft 27 carries a sprocket 30 which may be readily exchanged for one of different size, and this sprocket is connected by a 65 chain 31 with a sprocket 32 which may also be readily changed in size. An idler 33 serves to take up the slack in the chain 31. Sprocket 32 is carried by a shaft 34 which carries a sprocket 35 which, by the changes 70 in gears heretofore mentioned, may be driven at any desired speed relative to the main shaft. Running over sprocket 35 is a chain 36 which also runs over a series of sprockets 37 (dotted lines Figure 1), one of which 75 is mounted loosely upon each of the shafts 19, 20, 21 and 22 and connected to their appropriate shafts by friction clutches 38, so that the shafts 19, 20, 21 and 22, if unobstructed by anything materially resisting the movement of cross bars 14', 15', 16' and 17', will be forwarded by the friction drives.

Stitches 40 (see Figure 4) of any desired standard type, are arranged in the usual 85 way to form staples and drive them into the material passing through the cleat guides 11, binding wires being led to these stitchers over the rollers 41. The stitchers are intermittently operated by the vertical 90 reciprocation of a cross head 42, by means of pitmen 43, these pitmen at their lower ends being carried by eccentrics 44, mounted on the drive shaft 24. The resistance offered by the binding wires and the stitching mechanism is sufficient to prevent the friction driving mechanism from advancing any of the box material through the machine past the stapling plane. Up to this point the 95 mechanism and operation is well known and 100 disclosed in the specification and drawings of United States Letters Patent No. 1,140,297. The mechanism referred to for positively feeding the box material step by step past the stapling plane, in order to 105 receive the fastening staples, is not entirely satisfactory, and is not capable of adjustments of such character as to permit driving the staples at variable distances from each other.

The object of our present invention is to provide a mechanism, capable of adjustments such as those mentioned, for positively advancing the box material past the stapling plane step by step.

On each shaft 19, 20, 21 and 22 is a gear 50 which meshes with one of four gears 51, 52, 53, and 54, which will, therefore, control chains 14, 15, 16 and 17, respectively. The four gears 51, 52, 53, and 54 are journaled upon a sleeve which carries an arm 55, and this sleeve is journaled upon a fixed shaft 56 supported in suitable brackets 56' (Figure 5). Secured to arm 55 is a casting having two sets of segmental rack teeth 57 and four pawls 58, one of which is shown in Figure 2. One of these pawls is arranged alongside of each of the gears 51, 52, 53, and 54. The two segmental racks 57 are engaged by segmental racks 59, carried by a rock shaft 60 which is operated by means of an arm 61. The arm 61 is engaged by one end of a pitman 62 which is pivoted to its other end upon the wrist pin 63, carried by one of the eccentrics 44. That end of pitman 62 which is connected to arm 61 is provided with a clamping bolt 63' which passes through a curved slot 64 in arm 61, said slot being concentric with wrist pin 63, when arm 61 is at the extreme of its movement toward the left in Figures 2 and 4. By this arrangement, pitman 62 may be adjusted relative to arm 61, so that the stroke of arm 61 may be increased or diminished, without varying the extreme of the forward movement of the pawls 58, said extreme being always at the point indicated in Figures 2 and 4.

Each gear 51, 52, 53 and 54 is provided with a circumferential slot 65, Figures 2 and 4 so that each gear may carry any desired number of adjustable teeth 66 circumferentially adjustable by clamping nuts 67. For convenience the rear tooth 66 of each gear is arranged at the rear end of its slot 65, and each gear 51, 52, 53 and 54 is then so meshed with its appropriate gear 50 that the cross bar of the chain controlled by that gear 50 will be the required distance from the stapling plane whenever the rear tooth 66 has been advanced by the adjacent pawl 58. The gears 51, 52, 53 and 54 are so proportioned relative to the gears 50 and the lengths of the cleat-advancing chains, that a complete cycle of the chain will be produced by a whole number of revolutions of the large gear, and the adjustment will be such that when this gear has been forwarded by its appropriate pawl 58, engaging with the final tooth 63, the cross bar of the chain controlled by that gear will be spaced from the stapling plane a distance equal to the desired distance between the rear end of the cleat and the desired position for the last staple to be driven into that cleat. The

other teeth 66 may then be properly adjusted by setting the cross bar back to successively farther distances from the stapling plane, in a manner readily apparent. In order to provide the necessary advancement of the cross bar which drives the final cleat of each box blank, after the final cleat has passed the stapling plane, the gear controlling this cross bar will be provided with one or more additional teeth 66. It is noted that, if a cleat is of such length that a variation in spacing of the fastening staples is desired, this variation will be readily obtained by an appropriate spacing of the teeth 66, any advancement step, less than the maximum determined by the setting of pitmen 62 relative to arm 61, being obtainable at any point in the series. When a variation from the maximum is provided, it will be noted that the pawl 58, for that particular step, will have a certain amount of play before engaging the tooth 66 which is adjusted at less than the maximum spacing.

In operation, the cross bars, as soon as they reach the shaft 19, are withdrawn from between the cleats of the forming blank and are thereupon quickly forwarded in succession by the friction-driving means. By the time the cross bar of this chain has reached the feed end of the machine, the operator will place a cleat in front of it and further forward movement of the cross bar will then be obstructed except as it is accomplished by the positive feed mechanism. This positive feed mechanism comes into action successively on the successive chains. In the machine shown, gears 51, 52, 53 and 54 are of such size that they make two complete rotations for each cycle of the chains but the pawl feed is only effective every other rotation because the intermediate rotation is produced rapidly by the friction driving means and the teeth 66 merely pass at high speed beneath the pawls.

Having now fully described and ascertained my said invention and the manner in which it is to be performed, I declare that what I claim is:

1. A machine for use in making boxes comprising, in combination, a work support; mechanism to secure binding wire to box parts; and means for causing relative progression between said mechanism and the box parts comprising, a reciprocating pawl, a rotative element cooperating with said pawl and provided with a plurality of independent angularly adjustable teeth adapted to be engaged by the pawl; said machine being adapted to operate without interruption on materials for a plurality of boxes.

2. A machine for use in making boxes comprising, in combination, a work support; mechanism to secure binding wire to box parts; and means for causing relative pro-

gression between said mechanism and the box parts comprising, a reciprocating pawl, a rotative element cooperating with said pawl and provided with a plurality of independent angularly adjustable teeth adapted to be engaged by the pawl and to vary the effective throw thereof; said machine being adapted to operate without interruption on materials for a plurality of boxes.

10 3. In a box blank machine a work-holder to receive and position the materials for a box blank, means to cause said work-holder to move forward intermittently, said means comprising a reciprocating pawl, a rotative element having connection with said work holder co-operating with said pawl and provided with a plurality of independent angularly adjustable teeth adapted to be engaged by the pawl; said machine being 15 adapted to operate without interruption on materials for a plurality of boxes.

4. A box blank machine comprising a work-holder, yielding driving means for forwarding said work-holder and positive forwarding means comprising a rotative element connected to said work-holder, a reciprocating pawl and a plurality of angularly adjustable teeth carried by said rotative element in position to be engaged by said pawl; 20 said machine being adapted to operate without interruption on materials for a plurality of boxes.

5. In a box blank machine a work-holder to receive and position the materials for a 25 box blank, stapling mechanism to secure said materials together, yielding driving means for forwarding said work-holder and positive forwarding means for moving said work-holder intermittently, said positive 30 forwarding means comprising an independent rotative element, a reciprocating pawl co-operating with said stapling mechanism, a plurality of angularly adjustable teeth carried by said rotative element in position to 35 be engaged by said pawl, and means for varying the throw of the pawl without altering the extreme of its forward movement.

6. In a box blank machine, a work-holder comprising a plurality of sets of endless 40 chains, one set for each section of a box blank, yielding driving means for forwarding said chains and a plurality of positive driving means for forwarding said chains step by step, said positive driving means being 45 independent of each other and capable of individual adjustment.

7. A box blank machine comprising a plurality of sets of feed chains, one set for each 50 section of a box blank, yielding driving 55 means for forwarding said chains and positive forwarding mechanisms for said chains, each of said positive forwarding mechanisms comprising a rotative element connected to one set of the chains, a reciprocating pawl, and a plurality of angularly ad-

justable teeth carried by said rotative element in position to be engaged by said pawl.

8. A box blank comprising stapling mechanism, a plurality of sets of feed chains, one set for each section of the box blank, 70 yielding driving means for forwarding said chains and positive forwarding mechanisms for said chains, each of said positive forwarding mechanisms comprising an independent rotative element controlling one set 75 of the chains, a reciprocating pawl co-operating with the stapling mechanism, a plurality of angularly adjustable teeth carried by said rotative element in position to be engaged by said pawl and means for varying the throw of the pawl without altering the extreme of its forward movement.

9. In a box blank machine, stapling mechanism, a plurality of sets of feed chains, one set for each section of the box 85 blank, yielding driving means for forwarding said chains and positive forwarding mechanism for advancing said chains step by step, each of said positive forwarding mechanisms comprising a rotative element 90 connected to one set of the chains, a reciprocating pawl actuated by a pitman, the inner end of which is connected to one of the eccentrics driving the stapling mechanism, means for adjusting the outer end of 95 the pitman to vary the throw of the pawl, and a plurality of angularly adjustable teeth carried by said rotative element in position to be engaged by said pawl.

10. A box blank machine comprising 100 stapling mechanism, a plurality of sets of feed chains, one set for each section of the box blank, yielding driving means for forwarding said chains and positive forwarding mechanisms for advancing said chains 105 step by step, each of said positive forwarding mechanisms comprising an independent rotative element adapted to drive one set of the chains, a reciprocating pawl, a pitman connected to an eccentric driving the 110 stapling mechanism, the outer end of said pitman engaging a slotted arm whereby the throw of the pawl may be varied by adjusting the end of the pitman in the slot, and a plurality of teeth angularly adjustable in 115 a circumferential slot of the rotative element to be engaged by said pawl for the purpose set forth.

11. A machine for use in making boxes comprising, in combination, a work support; 120 stapling mechanism; and a driving mechanism to cause relative progression between said stapling mechanism and the work, comprising a plurality of independent, rotative elements mounted on a fixed 125 shaft; a series of angularly and independently adjusted teeth carried by each of said rotative elements; an arm journaled on said shaft and carrying reciprocating pawls, each adapted to successively engage the 130

- teeth of one of said series of adjustable teeth; and means for reciprocating said pawls by the motion of an eccentric which drives the stapling mechanism.
12. A machine for use in making boxes comprising a work support; stapling mechanism; and driving mechanism to cause relative progression between said stapling mechanism and the work comprising a driving arm; segmental racks carried by the outer end thereof, a rocking shaft, toothed segments mounted on said rocking shaft and engaging the segmental racks first mentioned, a rocking arm carried by said rocking shaft, said arm having a curved slot to adjustably accommodate the outer end of a pitman operated by an eccentric, a rotatable element carrying adjustable teeth clamped in desired positions in a circumferential slot and a pawl carried by said driving arm to act successively on said adjustable teeth and impart intermittent movement to said rotatable element.
13. A machine for use in making wire-bound boxes comprising work-forwarding means; fastener-setting mechanism; and means to cause relative progression between said mechanism and the work, comprising a yielding driving means and a positive driving means, said positive driving means comprising a series of selectively-spaced, adjustable members having connection with the work-forwarding means, and a reciprocating actuator adapted to propulsively engage each of said members in turn.
14. A machine for use in making wire-bound boxes comprising, in combination, work-forwarding means; fastener-setting mechanism; and means to cause relative progression between said mechanism and the work, including means to yieldingly advance said work-forwarding means during a portion of its travel; and means to positively advance said work-forwarding means during another portion of its travel in steps of controlled length to locate fasteners at selected points in the work; said positive driving means comprising a pattern of selectively-spaced members having connection with the work-forwarding means and a motion-imparting device adapted to propulsively engage successively the members of said pattern to advance the work-forwarding means distances corresponding relatively to said pattern.
15. A machine for use in making wire-bound boxes comprising, in combination, endless work-forwarding means; fastener-setting mechanism; means to yieldingly advance said work-forwarding means; and means to positively advance said work-forwarding means in steps of controlled length to locate a succession of fasteners in a unit of work at variable, selected points.
16. A machine for use in making wire-
- bound boxes comprising, in combination; endless work-forwarding means; fastener-setting mechanism; means to yieldingly advance said work-forwarding means; and means superseding said yielding advancing means to positively advance said work-forwarding means in steps of controlled length to locate a succession of fasteners in a unit of work at variable, selected points.
17. A machine for use in making wire-bound boxes comprising, in combination, endless work-forwarding means; fastener-setting mechanism; means to yieldingly advance said work-forwarding means; and means superseding said yielding advancing means to positively advance said work-forwarding means in steps of controlled length to locate fasteners at variable, selected points in the work, comprising a pattern of members having connection with the work-forwarding means, and a motion-imparting device adapted to propulsively engage each member in turn.
18. A machine for use in making boxes comprising, in combination, work-forwarding means; fastener-setting mechanism; and feeding means comprising a yielding driving means and a positive driving means, said positive driving means comprising a series of adjustable members having connection with the work-forwarding means, and a motion-imparting device adapted to engage said members successively.
19. A machine for use in making boxes comprising, in combination, work-forwarding means; fastener-setting mechanism; and work-feeding means including a yielding driving means and a positive driving means, said positive driving means comprising adjustable controlling members having connection with the work-forwarding means, and a motion-imparting device adapted to propulsively engage said controlling members successively to advance the work variable distances intermittently.
20. A machine for use in making boxes comprising, in combination, work-forwarding means; fastener-setting mechanism; and work-feeding means comprising a yielding driving means and a regulable positive driving means, said positive driving means comprising a series of selectively-spaced devices having connection with the work-forwarding means, and an actuator adapted to propulsively engage said devices in turn to advance the work variable distances corresponding to the spaces between said devices.
21. A machine for use in making boxes comprising, in combination, work-forwarding means; fastener-setting mechanism; and means to cause relative progression therebetween, including a yielding driving means and a positive driving means adapted to control said relative progression to locate fasteners at desired points on the work, said

- positive driving means comprising a series of members having connection with the work-forwarding means and spaced apart relatively according to the desired distances 5 between fasteners, and a motion-imparting device adapted to engage said members successively.
22. A machine for use in making boxes comprising, in combination, fastener-setting mechanism; a conveyer for box parts; means to yieldingly feed said conveyer; and means to feed said conveyer in steps of controlled length to present selected fastener-receiving points on the work to said mechanism, comprising a reciprocating actuator adapted during variable fractions of its throw to propulsively engage successively a series of members having connection with the conveyer.
23. A machine for use in making boxes comprising, in combination, work-forwarding means; fastener-setting mechanism; and means to cause relative progression between said mechanism and the work, including a yielding driving means and a positive driving means, said positive driving means being adapted to control the progression to locate fasteners at selected points on the work, and comprising an adjustable pattern of feed members for a unit of work having a fixed ratio of movement with the work-forwarding means, and a motion-imparting device adapted to engage said members successively and advance the work variable distances corresponding relatively to said pattern.
24. A machine for use in making boxes comprising, in combination, work-forwarding means; fastener-setting mechanism; and means to cause relative progression between said mechanism and the work, including a yielding driving means and a positive driving means, said positive driving means being adapted to control the progression to locate fasteners at selected points on the work, and comprising an adjustable pattern of feed members for a unit of work having a fixed ratio of movement with the work-forwarding means, and a motion-imparting device adapted to engage said members successively and advance the work variable distances cor-
- responding relatively to said pattern, said feeding means being constructed and arranged to present a succession of units of work to the fastener-setting mechanism and 55 locate fasteners in each unit according to said pattern.
25. A machine for use in making boxes comprising, in combination, endless work-forwarding means; fastener-setting mechanism; and means to cause relative progression between said mechanism and the work in steps of controlled length, comprising a ratchet wheel having adjustable teeth selectively spaced thereon and, a reciprocating 65 actuator adapted to propulsively engage said teeth successively.
26. A machine for use in making boxes comprising, in combination, endless work-forwarding means; fastener-setting mechanism; and means to cause relative progression between said mechanism and the work in steps of controlled length, comprising a ratchet wheel having adjustable teeth spaced apart variable distances corresponding relatively to the desired length of feed steps, and a reciprocating actuator adapted to propulsively engage said teeth successively and advance each tooth in turn a distance equal to the distance between the engaged tooth and 75 its predecessor.
27. A machine for use in making boxes comprising, in combination, work-forwarding means; binding-wire-applying mechanism; means to yieldingly advance said 80 work-forwarding means; and means to positively advance said work-forwarding means in steps of controlled length to locate fasteners at selected points relative to edges of work assemblies.
28. A machine for use in making boxes comprising, in combination, work-forwarding means; binding-wire-applying mechanism; means to yieldingly advance said 85 work-forwarding means; and means to positively advance said work-forwarding means in steps of controlled length to locate fasteners relative to edges of a succession of work assemblies.

In testimony whereof, I have signed my 100 name to this specification.

NEIL A. FOWLER.
